(57) CLAIM

The ornamental design for an ear, face and neck covering, as shown and described.

DESCRIPTION

FIG. 1 is a perspective view of an ear, face and neck covering showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a perspective view of the ear, face and neck covering, shown in an alternate configuration in use on a human subject.

In FIG. 8, a human subject is depicted using dashed lines for the purpose of illustrating the use of the ear, face and neck covering on a human subject and forms no part of the claimed design.

The broken lines shown on the surface of the article depict stitching that forms no part of the claimed design.
